VOLUME AND TEMPERATURE CONTROLLED FAUCET

Leronzo T. Reeves, Jr., Evanston, Ill.

Application October 4, 1946, Serial No. 701,140

5 Claims. (Cl. 277—64)

1

My invention relates to volume and temperature controlled faucets and more particularly to household faucets for dispensing water of the desired temperature.

With the foregoing in view, an object of my invention is to provide an improved volume and temperature controlled faucet.

A further object is to provide an improved faucet of this type wherein one of the volume or temperature is controlled by a rotary valve and the other is controlled by a reciprocal valve.

Other objects and advantages reside in the particular structure of the improved faucet, combination and arrangement of the several parts and in the particular method of operation, all of which will be readily apparent to those skilled in the art upon reference to the drawing in connection with the detailed description to follow wherein the invention is shown, described and claimed.

In the drawing:

Figure 1 is a longitudinal, vertical section taken substantially on the plane of line 1—1 of Fig. 2;

Fig. 2 is a bottom plan view of a faucet according to the invention;

Fig. 3 is a perspective view of the temperature control valve stem of the invention, apart from the faucet;

Fig. 4 is a top plan view with part broken away of the temperature control valve of the invention apart from the faucet;

Fig. 5 is a horizontal section through the faucet with parts removed and taken substantially on the plane of the line 5—5 of Fig. 1;

Fig. 6 is a plan view of the temperature control valve shaft apart from the faucet;

Fig. 7 is an elevation thereof;

Fig. 8 is a bottom plan view thereof;

Fig. 9 is an elevation of the volume control valve shaft apart from the faucet and with parts broken away and shown in section;

Fig. 10 is a plan view of an element of the volume control apart from the faucet;

Fig. 11 is a bottom plan of the volume control valve apart from the faucet;

Fig. 12 is a diagrammatic plan view of the temperature control valve in the normal position;

Fig. 13 is a fragmentary sectional view of a modification; and

Fig. 14 is a vertical section through a modification of the temperature control valve.

With particular reference to Fig. 1 of the drawing, 1 indicates a faucet casting which comprises a vertically disposed, hollow, cylindrical casing 20 having hot and cold water inlet openings 21 and 22, respectively, in the floor 23 thereof. The

2

inside surface of the floor 23 forms a flat and substantially circular seat for the temperature control valve 24, to be described later.

The opening of an outlet spout 25 opens into the casing 20 above the temperature control valve 24. The top of the casing 20 is closed by a cap 2 which is detachably secured to the casing 20 in any suitable manner. The cap 2 is provided with a central threaded aperture 26 in which is screwed the threaded volume control valve shaft 3. The upper end of the shaft 3 is provided with any suitable operating handle 27.

The shaft 3 is centrally bored to provide a relatively wide circular passage 28 at its upper end and a relatively narrow passage 29 at its lower end. A radial shoulder 30 connects the passages 28, 29 intermediate the ends of the shaft 3.

The top of the shaft 3 may be formed with a circular recess 31 to seat the circular handle or knob 32 of the temperature control valve shaft 4. The shaft 4 is of stepped cylindrical configuration complementary to the stepped bore 28, 29 of the shaft 3 in which it fits for relative turning movement therein. The radial shoulder 30 of such bore provides a seat for the lower end of the shaft 4.

The shaft 4 is provided with an H-shaped, splined bore or passage 33 (Fig. 8) which slidably receives the complementary H-shaped valve shaft extension or stem 5 which as here shown comprises a cylindrical shaft having diametrically opposed slots or keyways 34 extending longitudinally thereof for the greater part of its length, to receive the splines of the passage 33. The lower end 35 of stem 5 is unslotted and is rotatably seated in the circular recess 36 in the floor 23 of the casing 20.

Diametrically spaced prongs 37 depend from the lower end of shaft 4 and are so positioned as to comprise extensions of the splines of passage 33 and to have a sliding fit in the keyways 34 of the stem 5. Diametrically oppositely extending lugs 38 are formed on the outer surfaces of the prongs 37 to provide a seat for the lower end 39 of the shaft 3. An annular flange 40 depends from the lower end 39 of the shaft 3 and bears on the upper surface of the vertically reciprocable volume control valve 8.

The valve 8 (Figs. 1 and 11) is generally cylindrical shape and the upper end is formed with a circular flange 41 for a sliding fit in the chamber 20. The flange 41 is formed with a depending cylindrical skirt 42 to provide an annular recess between said skirt and the body of valve 8 wherein is seated the upper end of valve sup-

porting coil spring 50, which is concentric to the valve 8. The lower end of spring 50 is supported atop the temperature control valve 24. The valve 8 is axially bored as at 18 for a sliding fit on the stem 5 and the lower ends of prongs 37.

The lower portion of the volume control shaft 3 is unthreaded and is formed to provide a peripheral groove 43. The upper portion of the groove 43 is formed with diametrically opposed keyways 44 in the floor thereof to receive the slot 45 of a slotted washer 10. The washer 10 is formed with a central hole 46 to fit the floor of groove 43 and with an upstanding marginal flange 47 which provides a seat for the lower end of a volume control valve loading spring 9 (Fig. 1), concentric to the shaft 3. The upper end of spring 9 surrounds an annular boss 48 on the underside of cap 2 and seats against said underside of cap 2.

The temperature control valve 24 comprises a disc 7 of any suitable material and is formed with a central hub 51 which is formed with an H-shaped hole 60 therethrough for a press fit on the valve stem 5. The disc 7 is formed with a plurality of holes 52 therethrough and the upper and lower surfaces of the disc 7 are coated with heavy layers of rubber or resilient plastic 12 and 13 which is flowed into the holes 52 to anchor such layers in place. The valve 24 is formed with hot and cold water inlet openings 53 and 54, respectively, which, in size and shape correspond to the hot and cold water inlet openings 21, 22 in the floor 23 of the casing 20. Where the cold water pressure (for instance) is greater than that of the hot water, the size of the valve opening 54 may be reduced as shown by the broken line 55 (Fig. 4) to compensate for such inequality.

An edge portion of the valve 24 may be arcuately cut away to provide stops 56 and 57 which alternately engage a stop lug 58 which projects radially inwardly from a wall of the casing 20 whereby to limit rotary movement of the valve 24 in both directions.

It is to be noted that the coated lower surface 13 of valve 24 provides a washer for such valve and that the coated upper surface 12 provides a washer and seat for the volume control valve 8. The lower surface of the valve 8 is formed with an axial recess 59 to clear the hub 51 of the valve 24 when valve 8 is seated thereon.

If, as for instance when it is necessary to use a valve 24 with inlet openings 53, 55 of unequal size, the proper application of a new valve 24 can be assured by substituting an asymmetrically shaped keyway, holes, splines and the like for the symmetrical H-shaped keyways 34, holes 60, prongs 37, passage 33 of the several parts.

Also, by providing a relatively steep pitch of the threads on the threaded portion of shaft 3, while at the same time making the valve loading spring 9 substantially stronger than the valve supporting spring 50, the volume control valve will be continuously urged towards its seat 12 whereby to become a self closing valve.

In operation, temperature is controlled by rotating the temperature control knob 32 in either a clockwise or counterclockwise direction, which transmits such motion through the shaft 4 and stem 5 to the temperature control valve 24. Such valve is normally partly open with each of the inlets 21 and 22 equally, though only partially uncovered as is diagrammatically shown in Fig. 12. With the parts in the Fig. 12 position, and assuming the volume control valve to

be open, equal amounts of hot and cold water will flow through valve 24. If valve 24 is turned in a clockwise direction, less hot but more cold water will be permitted to flow until, when the valve is turned until shoulder 57 engages the stop lug 58, the hot inlet 21 will be entirely cut off while the cold inlet 22 will be wide open. Turning the valve 24 in a counter-clockwise direction will obviously have an opposite result.

Volume is controlled to any desired degree by raising the volume valve 8 an appropriate distance from the seat 12 and this operation is entirely independent of the operation of the temperature control valve. Moreover, the splined connection between the shaft 4 and stem 5 permits the knob 32 of the shaft 4 to move up and down without being unseated from the recess 31 in handle 27. Indeed, the engagement of the lower end of shaft 4 with the radial shoulder 30 of axial bore 28 of shaft 3 causes shaft 4 to move upwardly with shaft 3 while the engagement of the lower end 39 of the shaft 3 with the lugs 38 of the prongs 37 forces the shaft 4 to move downwardly with the shaft 3. The telescopic relation of shaft 4 with stem 5 permits this action.

Where a spring closed volume valve is not desired, the washer 10 and spring 9 can be removed readily without special tools or otherwise modifying the valve. Indeed both valves and their associated parts can be readily removed from the casing 20 for disassembly when the cap 2 is removed. The stem 5 with the disc valve 24 then slips readily out of the bore of shaft 4. As the valve 24 and stem 5 are connected with a press fit they are replaced as a unit when the washers 12 and 13 become worn. Alternatively, (Fig. 13) the valve 24 may be readily detachable from the stem 5 in a number of ways, as by reducing the diameter of the lower end 72 of the stem 5, providing a correspondingly sized hole 73 in the valve 24 and applying said valve to the stem from the lower end. This structure provides a shoulder 70 on the stem 5 which bears against the upper surface of the hub 71 to prevent the valve from sliding up stem 5 under water pressure. Shims can be inserted between said shoulder 70 and hub 71 to compensate for wear of the lower washer 13 or an initial misfit. After the stem 5 is removed from shaft 4, prongs 37 of the latter may be pressed together and shaft 4 may be withdrawn upwardly out of shaft 3.

Fig. 14 illustrates a further modification of the valve 24 wherein the diameter of the upper washer 112 is reduced to permit the lower end of the spring 50 to seat directly on the disc 7 of the valve rather than partially on the washer and partially on the stop lug 58.

Also, valve 24 may not be press fitted on stem 5 but merely slipped on stem 5 from the top. Hub 51 of valve 24 will then rest on the shoulders at the lower end of keyways 34 of stem 5, thereby holding end 35 of stem 5 in place in recess 36 so long as valve 24 is held down by spring 50. In this form, spring 50 is strong enough to resist maximum water pressure even when expanded as it is when valve 8 has been raised to increase volume of water flow.

When temperature control shaft 4 is rotated, stem 5, valve 24, spring 50, and valve 8 are rotated because friction between flange 40 and valve 8 is less than between the other named parts.

When handle 27 is rotated to control volume, flange 40 rotates but valve 8 which it bears against, does not. This allows valve 8 to settle on valve 24 without disturbing its position. Fric-

tion may be reduced (though it is not necessary) by inserting a set of small ball bearings between flange 40 and valve 8.

Washer 13 may be attached to base 23 and washer 12 to the bottom of valve 8, each conforming in shape to the surface to which attached, perforations 52 being eliminated.

While I have shown and described what is now thought to be a preferred form of the invention, it is to be understood that the same is susceptible of being expressed by other embodiments. Consequently, I do not limit myself to the precise structures or combinations shown and described hereinabove, except as hereinafter claimed.

I claim:

1. A mixing valve, comprising a casing having sides and a floor, at least two fluid inlets in the floor of said casing, a mixing valve seated on the floor of said casing for turning movement in a plane parallel to the floor of said casing, a washer integral with said valve and interposed between the same and said casing floor, a second washer integral with said valve and carried by the upper surface of said valve, at least two inlet apertures through said washers and valve, means for turning said valve to vary the relative amounts of liquids admitted through said inlets and apertures, a volume control valve within said casing, and means for moving said volume control valve into and out of sealing engagement with said second washer to control the volume of fluid passing said first valve.

2. A mixing valve, comprising a casing including a wall, at least two fluid inlets in said wall, a mixing valve seated on said wall, a washer carried by said valve and interposed between said valve and wall, a second washer carried by said valve on a side thereof remote from said wall, at least two apertures through said washers and valve, means mounting said valve for turning movement along said wall whereby to vary the proportions of liquids passed through said inlets and apertures, means for turning said valve, a volume control valve within said casing, and means for moving said volume control valve into and out of engagement with said second washer to vary the volume of fluids passed by said mixing valve.

3. The structure of claim 1, said means for turning said mixing valve comprising a stem, said volume control valve comprising a reciprocable valve and a shaft, said shaft being concentrically disposed about said stem for telescopic movement

relative thereto as said shaft is reciprocated, a second shaft having a splined, telescopic connection to said stem, said second shaft being concentrically disposed within said first shaft and being connected thereto for reciprocation therewith.

4. A mixing valve, comprising a casing including a flat wall, at least two fluid inlets formed in said wall, a flat mixing valve seated on said wall, said valve having opposed inner and outer faces, inner and outer washer means carried by said faces, at least two apertures through said valve and washer means, said wall comprising a valve seat for outer washer means of said valve, said outer washer means sealing off said inlets from each other, means mounting said valve for turning movement along said wall whereby to vary the proportions of liquids passed through said inlets and apertures, means for turning said valve, a volume control valve within said casing, and means for moving said volume control valve into and out of engagement with said inner washer means of said mixing valve to vary the volume of fluids passed by said mixing valve.

5. A mixing valve, comprising a casing including a wall, said wall being formed with at least two fluid inlets therein, a mixing valve seated on said wall, said mixing valve being formed with at least two inlet apertures therein and at least one outlet aperture therein, said valve comprising a pair of opposed surfaces, washer means carried by one surface of said mixing valve between the same and said wall to seal off said inlets from each other, said wall comprising a seat for said washer means, a second washer means carried by the other surface in concentric relation to said outlet aperture, a volume control valve, and means mounting said volume control valve for reciprocable movement into and out of engagement with said last-named washer means.
